FRANK DAVID BUTLER, OF BURLINGTON, IOWA.

VALVE MECHANISM.

1,157,081.

Specification of Letters Patent. Patented Oct. 19, 1915.

Application filed March 5, 1915. Serial No. 12,269.

To all whom it may concern:

Be it known that I, FRANK D. BUTLER, a citizen of the United States, a resident of Burlington, in the county of Des Moines and State of Iowa, have invented new and useful Improvements in Valve Mechanism, of which the following is a specification.

My invention relates to improvements in valve mechanism and particularly, valve mechanism for steam locomotives.

One of the objects of this invention is the provision of a new form of slide valve.

Other objects include improvements in details of construction and arrangement, whereby an efficiently operating mechanism of the type described is provided.

To the accomplishment of the foregoing and such other objects as may hereinafter appear, my invention consists in the construction, combination and arrangement of parts hereinafter described and then sought to be defined in the appended claims, reference being had to the accompanying drawing forming a part hereof and which shows merely for the purposes of illustrative disclosure, a preferred embodiment of my invention, it being understood that various changes may be made in practice within the scope of the claims, without digressing from my inventive idea.

In the drawings, Figure 1 is a vertical longitudinal section through a cylinder and valve, constructed according to my invention; Fig. 2 is a vertical transverse section through a cylinder, valve and connecting ports or passages; Fig. 3 is a top plan view of the valve; Fig. 4 is a vertical longitudinal section of the valve.

I provide an improved valve construction which gives a double steam admission and a double exhaust, this being controlled by a particular form of valve. In Fig. 2, the section shows substantially half of a locomotive, 2 indicating the flange providing the boiler seat, 3 being the steam supply passage and 4 the exhaust passage. The steam supply passage leads into the head of the steam chest 5, which is located on top of the cylinder 1. The valve seat 6 is flat as shown, and provided with the pairs of passages or openings 7 and 8, which are connected together as shown, and lead into the ends of the cylinder as at 9. These ports or passages serve alternately as inlet and exhaust ports. At opposite ends of the valve seat 6, I provide the passages 10, which con-

vey the exhaust steam through the port 11 to the exhaust passage 4, these ports being shown best in Figs. 1 and 2. The valve is operated by the usual stem and connected parts. This valve is substantially rectangular in shape as shown in Fig. 3, and has a central and circular flange portion 12 which extends about the opening of the steam supply passage 3. This circular flange is provided with a shelf or seat 13 to receive the packing rings 14 and 15. 14 is a resilient ring split as at 16 and these rings are forced against the cover of the steam chest by means of the weighted levers or arms 17 pivotally mounted as at 18 on top of the valve, whereby a steam tight connection is continuously maintained.

As stated before, the steam is admitted through the passage 3 into the chamber or compartment, provided by the circular flange 12. An intermediate port or passage 19 communicates therewith and in addition, the end ports or passages 20 communicate therewith, these last mentioned ports being formed in built-up or extended portions 21, which extend across the valve longitudinally, from end to end, as shown in Figs. 3 and 4, particularly. The exhaust ports or passages are indicated as 22 and open at 23 outside of the chamber or compartment provided by the circular flange 12. It is with this outer chamber or compartment, that is, the one provided between the walls of the steam chest 5 and the walls of the valve 90 itself, that the exhaust passages 10 communicate.

It is to be noted that the chamber or compartment provided by the circular flange 12 of the valve is the live steam compartment 95 and that the chamber or compartment provided outside of this circular flange 12 and between the side walls and top of the steam chest may be termed the exhaust steam compartment. This is an important feature, as 100 it materially assists in the prevention of steam leakage around the steam chest gaskets, and valve steam packing.

The operation of the valve is obvious from the above description. Referring to Fig. 1 particularly, it is seen that when the valve is positioned to the right, the forward side of the piston is open to live steam admission, through the registration of the forward and intermediate admission ports 19 110 and 20 with the forward cylinder ports 7 and 8. It is likewise seen that the rear side

of the piston is open to exhaust passages 10 and 11 by and through the opening allowed by the rear edge of the valve over the rear cylinder port 7 and by and through the registration of the rear exhaust port 22 in the valve with the rear cylinder port 8. When the valve is going toward its closing position, its travel is back, the travel of the valve being in the same direction as the travel of the piston. Now then, when it moves to the position shown in Fig. 1, the cut-off occurs between said admission ports in the valve and said cylinder ports previously described. From the point of cut-off to the point of release, shown in Fig. 1, expansion occurs on the forward side of the piston. At the point of release shown in Fig. 1, the forward side of the piston is about to be opened to exhaust, hence the release, the rear side of the piston is being cut off from its exhaust. From position shown in Fig. 1, exhaust occurs on the forward side of the piston for the remainder of the back stroke of said piston and on the next forward stroke until the piston reaches a like position as shown in Fig. 1, forward of its central position. From position shown in Fig. 1 until the piston nears its back crank dead center, the space back of the piston is shut off, hence is on compression. As the piston nears its back crank center, admission occurs to the rear side of piston by and through the registration of the rear admission port 20 and intermediate admission port 19 with the rear cylinder ports 7 and 8.

The exhaust on the forward side of the piston being controlled by the amount of opening allowance of the forward edge of the valve over the forward cylinder port 7 and the amount of registration of the forward exhaust port 22 with the forward cylinder port 8. The forward piston travel cycle is like unto the rear piston travel cycle, just described.

It is therefore seen that I have provided a slide valve which will give double admission and double exhaust, whereby a very efficient mechanism of this character is provided.

What I claim is:

1. In combination with the cylinder of a steam engine, having inlet and exhaust ports, a steam chest having a steam inlet connection, a valve for controlling the passage of steam from the inlet connection to the cylinder, said valve having a circular flange, a plurality of packing rings supported by said flange, the lower packing ring being split and a plurality of weighted levers engaging said split ring to force the uppermost ring into engagement with the cover of the steam chest to form a continuous steam tight fit.

2. A slide valve for a steam engine having a body portion, a flange upstanding there-

from, said body portion having a plurality of steam supply ports with which the chamber or compartment provided by said upstanding flange, is in constant communication, said ports or passages serving as inlet passages for live steam, said body portion also having ports or passages opening without said upstanding flange, said ports or passages being exhaust ports or passages.

3. A slide valve for a steam engine, including a body portion substantially rectangular in shape and having a circular upstanding flange, said body portion having a plurality of built-up or extended portions which provide ports or passages communicating within said upstanding flange and which provide inlet ports or passages for live steam, said body portion also having an additional inlet passage located intermediate said first mentioned ports or passages and communicating within said upstanding flange, said body portion also having a plurality of other ports or passages communicating without said upstanding flange and providing exhaust ports or passages for the exhaust steam.

4. In combination with a cylinder of a steam engine having inlet and exhaust ports for each end, a reciprocating slide valve therefor, having an upstanding flange portion adapted to receive steam from the source of steam supply, a plurality of inlet ports or passages communicating within said flange portion and adapted to register with said inlet and exhaust ports.

5. In combination with a cylinder and steam chest of a steam engine, said steam chest being mounted on said cylinder and having a substantially flat valve seat with ports or passages communicating with opposite ends of said cylinder, a reciprocating slide valve fitting within said steam chest and having an upstanding flange portion adapted to embrace the inlet from the source of steam supply, said valve having a plurality of inlet ports or passages communicating within said upstanding flange and adapted to register with said inlet and exhaust ports for the cylinder, said valve also having a plurality of exhaust ports communicating without said upstanding flange and adapted to register with said inlet and exhaust ports for said cylinder, these ports or passages being so arranged as to provide a double admission and a double exhaust.

6. In combination with a cylinder and steam chest of a steam engine, the steam chest being mounted on the cylinder and having communication with a source of steam supply and also having a substantially flat valve seat with a plurality of ports

- or passages leading to each end of said cylinder, a reciprocating slide valve positioned on said seat and having an upstanding flange engaging the top of the steam chest 5 about the inlet connection, said valve having a plurality of inlet ports or passages communicating within said upstanding flange and adapted to register with the inlet and exhaust passages for said cylinder, said 10 inlet ports or passages in said valve including a pair arranged on opposite sides of said valve and an intermediate port or passage, extending longitudinally across said valve, said valve also having exhaust ports or 15 passages communicating with the steam chest without said flange portion and adapted to register with the inlet and exhaust ports for said cylinder, said exhaust ports or passages in said valve being disposed between the side 20 inlet ports or passages and the intermediate inlet port or passage in said valve, the extreme edges of the valve providing an exhaust opening and cut-off in the other of said plurality of inlet and exhaust ports of 25 said cylinder, whereby a plurality of ports are provided for the admission of steam to one end of the cylinder and a plurality of ports are provided for the exhaust of steam from the other end of the cylinder.
- 30 7. In combination in a steam engine, having a cylinder and piston, a steam chest thereon having communication with a source of steam supply and with a steam exhaust, an enlarged flat valve seat provided in said 35 steam chest, a slide valve mounted thereon, said cylinder having a plurality of pairs of inlet and exhaust ports or passages leading to either end thereof, said valve having a flange portion embracing said inlet connection, a plurality of ports or passages in said valve in constant communication with the chamber or compartment provided by said flange portion, and a plurality of ports or 40 passages in said valve in communication with the chamber or compartment provided in the steam chest without the flange portion of said valve. 45
8. In combination in a steam engine, having a cylinder and piston, a steam chest thereon having communication with a source of steam supply and with a steam exhaust, an enlarged flat valve seat provided in said steam chest, a slide valve mounted thereon, said cylinder having a plurality of pairs of inlet and exhaust ports or passages leading 50 to either end thereof, said valve having a flange portion embracing said inlet connection, a plurality of ports or passages in said valve in constant communication with the chamber or compartment provided by said flange portion, and a plurality of ports or 55 passages in said valve in communication with the chamber or compartment provided in the steam chest without the flange portion of said valve, said flange portion of the valve having packing rings, and means for holding said packing rings against the top of the steam chest about the inlet connection to form a continuous steam tight joint. 60
